UNITED STATES PATENT OFFICE.

JAMES D. McCOY, OF BOSTON, MASSACHUSETTS, ASSIGNOR TO UNDERWOOD TYPE-WRITER COMPANY, OF NEW YORK, N. Y., A CORPORATION OF DELAWARE.

TYPE-WRITING MACHINE.

1,290,765.

Specification of Letters Patent.

Patented Jan. 7, 1919.

Application filed February 21, 1918. Serial No. 218,446.

To all whom it may concern:

Be it known that I, JAMES D. McCOX, a citizen of the United States, residing in Boston, in the county of Suffolk and State of Massachusetts, have invented certain new and useful Improvements in Type-Writing Machines, of which the following is a specification.

My invention relates to typewriting machines, and is herein disclosed as applied to an Underwood typewriting machine. Such machines are being used for purposes of bookkeeping, even in small offices where the machine is only used for part of the time for this purpose, and in such methods of bookkeeping it has hitherto been customary to make the ledger-sheet in the form of a carbon copy of the original statement or bill. Under some conditions, especially in small businesses, where the ledger-sheet is likely to remain only partly filled for a very long time, so that the carbon impressions thereon might become smudged from handling, it has been found desirable to make the ledger-sheet an original while the statement is in the form of a carbon copy. Since the ledger-sheet is usually wider than the statement-sheet, the ledger-sheet, when being adjusted, will often completely conceal the statement-sheet on which the carbon copy is to be written, thus rendering it difficult to align or register the statement and the ledger-sheet.

To overcome such difficulties of collation or alinement, and also to overcome certain other analogous difficulties, I provide a front-collating-table on which a statement-sheet may be adjusted and alined against the end gage and then held in such position of alinement while a ledger-sheet is being adjusted in front thereof.

To secure the necessary accuracy of adjustment of the statement-sheet, the table may be provided with both an end and a side gage and also a device adapted to hold the sheet against either the end or the side gage, or both, while another sheet is being adjusted in front of the statement-sheet. Since the end gage is useful not only in writing statements but also may be useful in alining letters and other work-sheets, such as are frequently used when the machine is not being used for bookkeeping, the end gage is made adjustable so that it may serve for the

various kinds of work-sheets which the machine is likely to be used for.

According to my invention, the holding-device for keeping the statement-sheet in position may be swung clear of the statement-sheet and clear of the ledger-sheet, after the ledger-sheet has been clamped in position by the usual feed-rolls. Then the usual feed-rolls will feed the ledger-sheet and the statement-sheet around together.

In order to obtain a structure for filling the above requirements, it might be supposed that the added weight of the necessary structures on the typewriter carriage would seriously interfere with the ease and quietness of the operation of the machine. I have found it possible, however, to provide that the adjusting table, such as has been shown in prior applications, may carry an adjustable-feed-roll at each side which forms the holding device, and which may be thrown around to ineffective position at any time. The upper end of the adjusting table may have its ends extended into the form of bent-over ears, which are adapted to support rods on which the end gage may be adjustable. Thus, the structure that carries the mechanism for adjusting the end gage is both light and out of sight and entirely out of the way of any work-sheets, but it may be easily reached if the typist puts his fingers around the end of the adjusting table.

Other features and advantages will hereinafter appear.

In the accompanying drawings,

Figure 1 is a perspective front view, showing my device as applied to the carriage of an Underwood typewriting machine.

Fig. 2 is a sectional side view of the same.

Fig. 3 is a fragmentary rear perspective, showing the mounting of the end gage.

The usual platen 10 of the Underwood typewriting machine is mounted on an axle 11, which is journaled in the end plates 12 and 13, and provided at its outer ends with knobs 14 by which it may be turned. In addition to this, it is provided with the usual line-space lever 15 variably effective by the usual connections on the usual line-space wheel 16.

A statement-sheet 17 may be inserted from the rear over the usual paper table 18 after casting off the usual feed-rolls 19 by the handle 20. The statement-sheet then may

be pushed around up at the front of the machine with its edge against a right-hand side-gage 21 until its end strikes an end-gage 22 which is adjustably mounted on a 5 collating or adjusting table 23. The statement-sheet may be then clamped in place by swinging the holding device (shown in the form of a roll 24) around the rod 25 until the device bears against the statement sheet 10 and holds said sheet in place. The table 23, as shown, is supported above the front of the platen 10, and slopes rearwardly so that sheets lie thereon at a convenient angle for adjustment. It is supported in this position 15 by brackets 26 to which it is firmly held by screws 27, which are screwed into ears 28 of the brackets and engage the surface of the table 23 at depressed portions 29, large enough and deep enough to accommodate 20 the heads of the screws 27, with the result that a work-sheet will slip, clear of the screw heads, smoothly over the table formed by the surface 23.

After the statement-sheet 17 is adjusted 25 in place, a ledger-sheet 30 may be adjusted in place by insertion in the usual manner over the rear paper table 18 up past the usual feed-rolls 19, and may be gaged against either or both of the side-gages 21 30 by means of a scale plate 31 forming part of each. If desired, in addition, one or more work-sheets 32 may also be inserted for any purpose desired in this form of bookkeeping. Between these sheets are inserted the usual 35 carbon sheets. The edge-gage 21 is long enough so that sheets may be accurately gaged sidewise thereagainst, even though they bend over the roll 24 and its mounting 32^a, and extend beyond the end-gage 22.

40 To enable this to be done, the roll 24 is placed at the lower extension of the box-frame 33 which forms a part of its mounting, and the upper edge 34 of said frame is the only point of the frame which projects 45 above the gage 21. The box-frame 33 is held steady by the arm 34, because said arm is extended downwardly as at 35, after it is extended downwardly as at 35, after it encircles the rod 25 at the point 36 and then is turned up again at 37 to embrace said 50 rod; thus, the extension 35 forms a bail embracing the rod 25 at each end.

In order to hold the roll 24 and its mounting in proper position on the rod 25, there is provided a spring 38 which bears against 55 the bail 35 and the rod 25. This structure enables the roll 24 to lie beside the gage 21 a considerable distance below the piece 34, thus requiring very little curving of a work-sheet to pass over the piece 34.

10 When all the work-sheets have been adjusted, the usual feed rolls 19 are thrown on by the handle 20 and then the roll 24 is swung around to position above the work-sheets, where it is shown in Fig. 1, clear of 5 the work-sheets, to enable them to be easily

fed along over the paper table 23 by the usual line-space mechanism.

In order to enable the mechanism to be of as broad utility as possible, there is provided a roll 24 slidably mounted on a rod 25 at 70 each side of the paper table 23, so that any or all work-sheets can be adjusted against either the left-hand turned-up edge 21 or the right-hand turned-up edge 21.

In order to enable statement-sheets with 75 various sized headings to be adjusted on this table 23, which is necessary in many kinds of business, the leading-edge gage 22 is adjustably mounted, as above stated, and to enable this mounting to be made so light as 80 not to materially add to the weight of the typewriter carriage, the table 23 is provided, at its upper end, with rearwardly-turned ears 39^a in which are mounted rods 40 extending behind the table 23 but parallel 85 thereto, and on these rods is slidably mounted a plate 39 which carries the gage 22 at its upper end.

To enable this gage to be easily adjusted and yet to be firmly held at any desired position, it is provided with a wing 41, at each side thereof, on which is fast a slide 42 having at its opposite ends two turned-up ears 43 embracing the adjacent rod 40, said slide 42 also having a boss 44 in which is mounted 90 a spring-pressed ball 45 adapted to bear against a slot 46 in the rod 40, thereby gaining the required friction. Since each of the ears 43 embraces the rod 40, the plate 39 is 95 compelled to move with its upper edge always parallel to itself.

Owing to the fact that the table 23 serves as the surface on which the work-sheets are adjusted, the plate 39 need not cover the whole of the opening across which the gage 100 22 moves. This enables the plate 39 to be made considerably smaller and thus lightens the structure.

For ease in assembling, the rods 40 are held in place at their upper ends by screws 110 47 which pass through the ears 39^a and they are also held in place at their lower ends by screws 48 which pass through the lower ears 49, the latter being in the form of turned-up edges of plates 50 held by screws 51 entered 115 into the plate 23. For convenience in alining, the machine includes the usual wing scales 52 adapted to show the line at which the type 53 will print. The brackets 26, which support the plate forming the table 23, may be mounted in one of the usual manners, for this purpose being fast on a transverse rod 54 which is fast in the shift frame.

In order to steady the brackets 26 they are formed at their upper ends at 58 to embrace a rod 59 mounted in the bracket 55 which is held in the shift frame by the usual screws 56 passing through the slots 57 in the brackets.

Variations may be resorted to within the 120 125

scope of the invention, and portions of the improvements may be used without others. Having thus described my invention, I claim:

5. 1. In a machine of the class described, the combination with a front paper-collating-table, of an edge gage thereon, a work-sheet-holding-device movable from effective to ineffective position and slidable along 55 said edge gage, an end gage extending across an opening in said table, and slidable devices on which said edge gage is mounted to permit said edge gage to be variably positioned.
10. 2. In a machine of the class described, the combination with a front paper-collating-table, of a side gage, and adjustable leading-edge gage on said table, and a work-holding-finger or device adapted to hold a work- 60 sheet against said table and against said leading-edge gage, while a second work-sheet is being adjusted against the side gage, said leading-edge gage being mounted behind the table and always moving parallel 65 to itself.
15. 3. In a machine of the class described, the combination with a front paper-collating-table, of work-holding-devices along the sides thereof, said devices being shift- 70 able from effective to ineffective position, a leading-edge gage, rods behind said table on which said leading-edge gage is slidable, and supports on said rods compelling the 75 leading-edge gage to always move parallel 80 to itself.
20. 4. In a machine of the class described, the combination with a front paper-collating-table, of work-holding-devices along the sides thereof, said devices being shift- 85 able from effective to ineffective position, a leading-edge gage, rods behind said table on which said leading-edge gage is slidable, and supports on said rods compelling the 90 leading-edge gage to always move parallel 95 to itself, said collating-table comprising a central opening in which said leading-edge gage is slidable, and an extension of said leading-edge gage forming a flat surface extending part way across said opening.
25. 5. In a machine of the class described, the combination with a front paper-collating-table, of turned-up edges thereon forming 100 side gages, work-holding-devices slidably mounted outside of said side gages and adapted to be thrown to effective or ineffective position around their slidable mounting, a leading-edge gage extending across an opening in said table, said leading-edge gage having a flat extension covering part of said opening, backwardly-turned 105 ears extending from said table forming a mounting for said leading-edge gage, rods behind said table carried by said ears, and devices slidable on said rods compelling the leading-edge gage to move parallel with 110 itself.
6. In a machine of the class described, the combination with a sheet-metal front collating-table, of turned-up edges thereon forming side gages, turned-up ears on said 115 turned-up edges, rods supported on said ears, work-holding-devices supported on said rods and slidable therealong and movable from effective to ineffective position, an adjustable leading-edge gage, backwardly- 120 turned ears on said table, rods mounted on said backwardly-turned ears, and turned-up ears on said leading-edge gage embracing said last-named rods to enable the leading-edge gage to be slidably moved along 125 the collating-table.
7. In a machine of the class described, the combination with a sheet-metal front collating-table, of turned-up edges thereon forming side gages, turned-up ears in said 130 turned-up edges, rods supported on said ears, work-holding-devices supported on said rods and slidable therealong and movable from effective to ineffective position, an adjustable leading-edge gage, backwardly- 135 turned ears on said table, rods mounted on said backwardly-turned ears, and turned-up ears on said leading-edge gage embracing said last-named rods to enable the leading-edge gage to be slidably moved along 140 the collating-table, brackets fast to the rear side of said table, and turned-up ends on said brackets adapted to support the lower ends of said last-named rods.
